UNITED STATES PATENT OFFICE.

CHARLES ITSCHNER, OF CHICAGO, ILLINOIS, ASSIGNOR OF ONE-HALF TO FRANKLIN P. SMITH, OF CHICAGO, ILLINOIS.

STAIRWAY.

1,291,905.

Specification of Letters Patent.

Patented Jan. 21, 1919.

Original application filed May 10, 1917, Serial No. 167,639. Divided and this application filed February 8, 1918. Serial No. 215,952.

To all whom it may concern:

Be it known that I, CHARLES ITSCHNER, a citizen of the United States, and a resident of Chicago, county of Cook, and State 5 of Illinois, have invented certain new and useful Improvements in Stairways, of which the following is declared to be a full, clear, and exact description.

This invention relates to stairways of that 10 type shown and described in my prior application for patent on stairways, filed May 10, 1917, Serial No. 167,639, and the subject-matter of this application has been divided out of said prior application.

15 The object of the present invention is to provide a stairway of simple, substantial and fireproof construction; another object is to provide a stairway of which the risers and soffit portions are made up in units, or 20 sections, each comprising a riser and soffit section ready for assembly in the building where the stairway is to be erected. With these and other objects and advantages in view, the invention consists in the several 25 novel features hereinafter set forth and claimed.

The invention is clearly illustrated in the accompanying drawing, in which:—Figure 1 is a vertical longitudinal section through a 30 fragment of a stairway embodying a simple form of the present invention, and Fig. 2 is a vertical cross section taken on the line 2—2 of Fig. 1, the concrete filler being omitted in this view.

35 Referring to said drawing, the stringers of the stairway are illustrated at 13, and are preferably constructed of sheet metal having their upper edges bent outward to provide flanges 15, and having their lower edges 40 bent inward to provide flanges 25. A plastering strip 25^a, may be secured to one or both of the stringers 13, as is desired, and said plastering strip may be secured thereto as, for instance, by rivets 25^b. The 45 stringers 13, are supported in place in the building in accordance with the usual practice as is well known to those skilled in the art to which this invention pertains.

Each step or unit comprises a soffit portion or section 11, and a riser 18, the soffit section having an upwardly bent, vertical end portion 18^a, which is spot-welded to the lower end portion of the riser, as at 18^b. Each

riser has the usual nosing 18^c, at its upper end, formed with the usual return bend 18^d, 55 which is flush with the tread of the step. The lower end of each riser is bent outward, as at 21^b, to provide a cove between the riser and tread of the step. The riser and adjacent soffit portion of each step are 60 connected by a bar or brace rod 23, riveted, or otherwise secured to the riser and soffit, and merely serves to hold the upper end of the riser in a braced condition until the concrete is filled in. The risers are secured 65 to the stringers by angle iron brackets 24, which are bolted or riveted to the risers and stringers. The soffit plates or sections 11, rest upon the inturned flanges 25, of the stringers and may be riveted thereto. Each 70 unit is connected to the adjacent ones by over-lapping the soffit sections and riveting or bolting them together at the places where they over-lap.

The tread of the stairway is formed by 75 filling in, with concrete 22, the spaces between the soffit sections and upper edges of the opposing bent ends 18^a, and 21^b, of the nosing of one riser and cove portion of the next adjacent riser thereabove and the upper 80 surface of said filler of concrete is leveled off, as shown in the drawing, to provide the tread.

As before stated, the upper end of each 85 soffit section and a riser are secured together at the plant where the parts are manufactured, and thus form units which may be delivered to the place where the stairway is to be erected. After the stringers have been secured in place, the units comprising a soffit section and riser are secured to the 90 stringers by fastening the angle iron brackets thereto with bolts and nuts 24^a, and also, by the bolts or rivets 25^b, which pass through the soffit section and inturned flanges of the 95 stringers. The brace rods 23, are then secured in place and the overlapping soffit sections riveted or bolted together after which the concrete 22, is filled in the spaces above the soffit plates and the upper edges of 100 the nosing and coves of the risers.

More or less variation of the exact details of construction is possible without departing from the spirit of this invention; I desire, therefore, not to limit myself to the 105 exact form of the construction shown and

described, but intend in the following claims to point out all of the invention disclosed herein.

I claim as new, and desire to secure by 5 Letters Patent:

1. In a stairway, a plurality of flat, overlapping sheet metal soffit sections secured together, said sections having upwardly bent portions at their upper ends terminating 10 above the tread portions of the stairway, risers, one secured to each upwardly bent portion of each soffit section above the tread portion, said risers having outwardly bent lower edges to form coves at the tread portions, and a pair of supporting stringers to 15 which said risers are secured.
2. In a stairway, a plurality of flat, overlapping sheet metal soffit sections secured together, each soffit section having an upwardly bent end portion at its upper end, terminating above the tread portion of the stairway, risers, one for each soffit section, and having at its lower end an outwardly bent cove portion, and at its upper end, a 20 nosing terminating in a return bend, each riser being permanently secured, above the tread portions, to the soffit section associated with it to form a unit, a pair of stringers, and brackets secured to the risers and adapted 25 to be secured to the stringers.
3. In a stairway, a plurality of flat, overlapping sheet metal soffit sections secured together, said sections having upwardly bent portions at their upper ends terminating 30

above the tread portions of the stairway, 35 risers, one permanently secured to the upper end of each soffit section above the tread portion, each riser being formed with an outwardly bent cove portion at its lower end, and with a nosing at its upper end terminating 40 in a rearwardly curved portion flush with the tread of the step and in alinement with the cove portion of an adjacent riser, a pair of stringers, means for securing the risers to the stringers, and a filler in the 45 spaces between the soffit sections and top of one riser and cove portion of the next adjacent one.

4. In a stairway, a plurality of flat, overlapping sheet metal soffit sections having upwardly bent end portions at their upper ends terminating above the tread portions, a plurality of risers, one for each soffit section and permanently secured to the upwardly bent end thereof above the tread portions, each riser having an outwardly curved cove portion at its lower end and a nosing at its upper end terminating in a rearwardly projecting edge portion flush with the tread of the step, and a pair of stringers, each 60 having an outwardly bent flange portion along its upper edge and an inwardly bent flange portion along its lower edge underlying the soffit section, and brackets secured to the risers and adapted to be secured to 65 said stringers.

CHAS. ITSCHNER.

Copies of this patent may be obtained for five cents each, by addressing the "Commissioner of Patents, Washington, D. C."
